UNITED STATES PATENT OFFICE.

MARTIN HARTMAN, OF UPPER SANDUSKY, OHIO.

MOP-HEAD.

No. 825,209.

Specification of Letters Patent.

Patented July 3, 1906.

Application filed May 18, 1905. Serial No. 260,932.

To all whom it may concern:

Be it known that I, MARTIN HARTMAN, a citizen of the United States, and a resident of Upper Sandusky, in the county of Wyandot and State of Ohio, have made certain new and useful Improvements in Mop-Heads, of which the following is a specification.

My invention relates to improvements in mop-heads and a holder for the same, its object being to produce a simple, cheap, and efficient mop head and holder which can readily be applied to a handle and can be conveniently shipped in bulk.

My invention consists of certain novel features of construction, arrangement, and combination of parts, as will be hereinafter fully described, and pointed out in the claims, reference being had to the accompanying drawings, in which—

Figure 1 is a top view of a mop head and holder. Fig. 2 is a bottom view of same. Fig. 3 is a vertical transverse section through the mop head and holder. Fig. 4 is a perspective view of the holder and retaining-bolt. Fig. 5 is a section through a mop-handle, showing method of attaching mop-head.

In carrying out my invention I use a mop made of mop-yarn, wicking, or other suitable material, which is here designated by the numeral 1. The mop holder or clamp 2 is made from a single piece of stout wire bent, as shown in Fig. 4, to form the two loops 3 and 4, which lie horizontally, the loop 3 overlapping the loop 4, leaving a space or eye 9, through which the bolt 5 is passed, thus preventing said loops 3 and 4 slipping past each other. The loops extend a suitable distance outwardly and the wire forming them is then bent downwardly and then inwardly toward the center, the bar 6 being continuous, while the bars 7 and 8 extend inwardly in opposite directions past the center of the holder, overlapping each other and lying side by side. By thus bending the wire forming the holder a space is left between the upper and lower bars of the holder, in which is placed the mop material or mop 1. Several strands of the mop are threaded over and under the lower bars of the holder, as shown in Fig. 3, and particularly around the overlapping ends of the bars 7 and 8, thus holding them tightly together and also preventing spreading apart of the bars 6, 7, and 8. If desired, several

strands of the mop may be threaded over and under side bars of the holder at either or both ends thereof, where they are bent, as shown in Figs. 1 and 2, thus forming an additional safeguard against spreading. The bolt 10, which is threaded at its lower end and squared below its head, is passed through the eye 9 and through the mop material or mop and screwed into a suitable handle, or the said bolt may be secured in an ordinary handle by the method shown in Fig. 5. As shown in this figure, the handle 11 has a longitudinal hole 12 bored into it a suitable distance and a transverse opening 13 at the lower end of the hole 12, extending through the side of the handle. The bolt, which, as before stated, has been passed through the mop and holder, is inserted into the hole 12 and screwed into a nut 14, passed into the transverse opening 13 from the side of the handle until the mop and holder is tightly fastened to the end of the handle. The squared portion of the bolt fits within the eye 9 of the holder and prevents turning of the same on said bolt while being applied to the handle. (Shown in Fig. 5.)

It will be observed that the mop or mop material will be held flat and that by bending the wire, as shown, to form a holder or clamp the said mop will be securely held in place and prevented from undue spreading and that by threading or interlacing the strands of the mop or mop material the parts of the holder or clamp are prevented from spreading. It will thus be seen that I provide a device which is simple, cheap, and efficient and can be conveniently handled while in use, as well as easily packed for shipment in large quantities.

Having thus described my invention, what I claim as new, and desire to secure by Letters Patent, is—

1. A holder for mops consisting of a single wire bent to form lower bars and upper loops, between which lower bars and upper loops a mop is to be passed, and means engaging the upper loops and mop to secure the same to a handle.

2. A holder for mops consisting of a single wire bent to form lower bars, and overlapping upper loops, between which lower bars and upper loops a mop is to be passed, and means passing through the said overlapping upper

loops and mop to secure the same to a handle.

3. A holder for mops consisting of a single wire bent to form upper and lower bars between which a mop is to be passed; the upper bars bent to form flat loops overlapping each other and forming a central eye, and a bolt or

pin passing through said central eye and mop to secure the same to a handle.
